APPARATUS FOR BONDING THE ENDS OF
WIRE ROPESFrank E. Stahl, Tonawanda, N. Y., assignor to
Columbus McKinnon Chain Corporation, Tonawanda, N. Y., a corporation of New York

Application March 17, 1936, Serial No. 69,342

6 Claims. (Cl. 113—99)

My invention relates in general to apparatus for holding wire rope which is being cut and subsequently welded. Reference is to be had to application Serial No. 69,341 upon Methods of bonding the ends of wire ropes which contains subject matter common to this application.

It is well known to those skilled in the art that in all wire rope, except that which is initially preformed, the wires and strands will fly apart and become unraveled when the rope is cut through, thus making it necessary when cutting or splicing such rope to provide a number of seizures.

Furthermore, when the rope is to have an anchor attached to the extreme outer end thereof, such seizures obviously cannot be used because they must be located as near the outer end as possible.

The principal object of my invention has been to provide an apparatus for holding wire rope as it is being cut without having to provide and to apply seizures to the ends of the rope.

Another object has been to provide an apparatus in which the individual wires and strands at the end of the rope may be securely held against unraveling without the use of seizures while being bonded together.

Another object has been to provide an apparatus which shall be inexpensive to manufacture and convenient to use.

The above objects and advantages have been accomplished by the device shown in the accompanying drawings. In the drawings, where I show the wire rope broken off, it is to be understood that the broken-off part is either connected to the reel of wire rope (not shown) or to the severed length, the other end of which has been previously bonded. In the drawings:

Fig. 1 is a fragmentary, perspective view of a length of wire rope having its end severed and bonded in the apparatus of my invention.

Fig. 2 is a front elevation of my apparatus.

Fig. 3 is a plan view thereof.

Fig. 4 is a fragmentary, side elevation of my invention, showing a transverse, sectional view, taken on line 4—4 of Fig. 2.

Fig. 5 is a fragmentary, transverse, sectional view taken on line 5—5 of Fig. 2.

Fig. 6 is a similar view taken on line 6—6 of Fig. 2.

Fig. 7 is a plan view of my apparatus showing a wire rope held therein after being severed.

Fig. 8 is a front elevation showing my apparatus in the positions assumed when the ends of the wire rope are being welded.

In Fig. 1, I show the end 10 of a length 19 of wire rope 18 which has been severed and bonded in my apparatus. As here shown, the ends of the wires and strands have been welded together and a cap 11 has been welded over the top, thus providing not only a bond for the strands and wires, but closing the end of the rope, sealing in the hemp cord, if the rope is so provided, and thus providing an end which is stiff and rigid and one which cannot unravel.

My invention which is shown in Figs. 2 to 8, inclusive, comprises a bench vise 12 having a front movable jaw 13 and a rear stationary jaw 14. The movable jaw is operated by means of the vise screw 15.

Arranged between the jaws 13 and 14 of the vise are two clamping blocks 16 and two clamping blocks 17 arranged in pairs. The blocks 16 are arranged at that side of the vise which receives the wire rope 18 as it comes from the reel (not shown), and the blocks 17 are arranged at the opposite side of the vise jaw for the purpose of clamping that portion of the rope which is to become the severed length 19. The blocks are so proportioned and positioned that a space 20 is provided between them for the accommodation of any suitable mechanical cutting tool, or an oxy-acetylene flame. One of the blocks 16 is pivotally secured to the coacting jaw 13 by means of a pivot pin 26, and the other block is likewise pivotally secured to its coacting jaw 14 by means of a similar pivot pin 26, see Fig. 6. Each of these pivot pins is arranged with its axis at right angles to the axis of the wire rope or to the axes of the grooves 33 of the blocks, such pivot pins being disposed preferably near the bottom of the block and in the central portion thereof, and each is preferably driven into a suitable aperture formed in the block. The pins have their ends protruding beyond the outer surfaces of the blocks and are pivotally disposed in apertures 27 formed in the jaws of the vise. Each of the blocks 16 and 17 is provided in its inner working face with a semi-cylindrical groove 33 for the accommodation and clamping of the wire rope. The blocks 16 are held in definite spaced relation with each other by means of a bolt 28, and the blocks 17 are likewise held together by means of a similar bolt 28 (see Fig. 5). Each of these bolts passes through an aperture 29 in one of the blocks of 50 each pair and into a screwthreaded aperture 30 in the opposite block of the same pair. The head 31 of each of the bolts is disposed in a countersunk aperture 32, the depth of the aperture being so proportioned in relation to the head 31 of the bolt 55

that the blocks of each pair can open slightly so as to permit the free passage of the wire rope therebetween, but the parts are, however, so proportioned that the blocks of each pair will be limited 5 in their relative movement so that they cannot be separated from each other far enough to allow the rope to become disengaged from the grooves 33 and thereby fall out from between the blocks. The adjacent surfaces 21 of the blocks of each 10 pair are so proportioned that there is sufficient clearance between them when the rope is clamped.

One of the blocks 17 is pivotally attached to the vise jaw 13 by means of a screw 36, and the other block 17 is likewise pivotally attached to the 15 jaw 14 thereof by means of a similar screw 36 (see Fig. 4). Each of the screws 36 is slidably and rotatably mounted in an aperture 37 formed in each of the blocks 17 and screw threaded to its respective vise jaw. The head 38 of each of 20 these screws is disposed in a countersunk aperture 39 formed in each of the blocks, the depth of which aperture is so proportioned in relation to the length of the screw 36 that there is some 25 space between the bottom of the aperture and the bottom surface of the head of the screw, which will permit some motion between each of the blocks and its coacting vise jaws. By this arrangement, each of the blocks 17 will be held to its respective vise jaw in such manner that 30 when the movable vise jaw 13 is opened, the blocks 17 attached thereto will be moved therewith and separated from the other block 17 attached to the jaw 14. By this construction the end of the rope which is being loosely held by the 35 block 16 may easily enter between the blocks 17 when another length of rope is to be severed and bonded.

A stop pin 41 is provided for the blocks 16 and a similar pin 41 is provided for the blocks 40 17. Each of these pins passes through both of the blocks of each pair and extends a slight distance beyond the outer faces of each block, so as to contact with the upper surfaces of the vise 45 jaws 13 and 14 and thereby act as stops to limit the inward rotation of the blocks upon their pivots, as shown in Figs. 2, 4, and 5.

When my apparatus is to be put into use, the vise jaws are opened and the wire rope 18 is threaded in between the blocks 16 and also in 50 between the blocks 17, the rope coming from the reel (not shown) being moved during such threading operation in the direction of the arrows shown in Figs. 2 and 3. The rope is extended on through the blocks until the place 55 where it is desired to sever the rope is located in the space 20 between the pairs of blocks 16 and 17, a trough and stop (not shown) being provided, if desired, for the reception and support of the wire rope as well as for the gauging 60 of the length thereof. After the rope has been drawn through the blocks 16 and 17 the predetermined length, the screw 15 of the vise 12 is used to move the jaw 13 toward the jaw 14 and to thus firmly clamp the wire rope between the 65 coacting blocks 16 and the coacting blocks 17. As hereinbefore stated, the pairs of blocks 16 and 17 are separated so as to provide a space 20 therebetween in which the rope may be severed by any suitable means. A saw, either 70 hand or power operated, may be used to sever the rope, and in some cases it may be necessary, when a saw is used, to provide a slot (not shown) in the vise jaws for the reception thereof. I have found, however, that an oxy-acetylene 75 flame is a very convenient means of severing the

rope, because of the fact that such a flame must be used for welding the strands and wires of the rope together at the rope ends and in the formation of the caps 11. After the wire rope has been clamped by the two interspaced pairs of blocks, 5 as shown in Figs. 2 and 3, it is ready to be severed in the formation of the length 19. When the rope is severed by an oxy-acetylene flame, gobs 42 of solidified metal will usually be formed on the severed ends of the rope, as shown in Fig. 7. 10

After the wire rope has been severed, as shown in Fig. 7, the screw 15 of the vise 12 is loosened slightly and the workman then grasps the portions of the rope extending outwardly from each of the pairs of blocks 16 and 17, and by bearing 15 down upon these portions causes the pairs of blocks 16 and 17 to be rotated, the blocks 16 rotating about the pivot pins 26, and the blocks 17 rotating about the pivot screws 36. The blocks are rotated through substantially 90°, which will 20 bring the ends of the two portions of the rope above the upper edge of the jaws 13 and 14 of the vise, as shown in Fig. 8. These severed ends will also project slightly beyond the pairs of blocks 16 and 17, in the position shown in Fig. 8. 25 The workman now, by the use of the oxy-acetylene flame, will burn off the gobs 42 from each of the rope ends, thus making a substantially even end. The workman will then also, by the use of this flame, weld together the wires and 30 strands of the upturned ends and will also deposit metal upon such ends, thereby forming the caps 11, shown in Figs. 1 and 8. In such welding and in the formation of the cap, the wires and 35 strands of the rope are welded together so as to make the extreme end of the rope one single integral piece, so that when the welded rope is released from the clamping action of the pairs of blocks 16 and 17, the wires and strands cannot 40 become unraveled or fly apart.

It is to be understood that after the rope has been severed and before the ends thereof are welded, the jaws of the vise are loosened just sufficiently to permit the operator to rotate the pairs of blocks 16 and 17 about their pivots, but 45 not enough to release the clamping action of the pairs of blocks upon the wire rope to such a degree as to permit the rope to become unraveled.

After the severed ends of rope have been welded, as above described, the vise jaws are released 50 and the pairs of clamping blocks are again rotated on their pivots in reverse direction so as to bring them to their initial positions where the stop pins 41 will contact with the tops of the vise jaws. The length of rope 19 (capped at each 55 end) is now removed from between the blocks 17. If the jaws have not been sufficiently released so as to permit the free passage of the rope between the blocks, the jaw 13 is further opened. As this jaw is opened, it will separate the blocks 60 17 because of their attachment to the jaws by the pivot screws 36, and thus permit the free passage of the rope therebetween. The wire rope 18 coming from the reel (not shown), with its end capped, is now moved along between the 65 blocks 16 and between the semi-cylindrical recesses of the blocks 17. The rope is continued on until the end engages with the stop (not shown) for the gauging of the next length 19, whereupon the vise jaw 13 is again clamped in 70 position, thus securely holding the rope between the jaws 16 and 17 ready to be severed at the place in the space 20 between the pairs of blocks, as hereinbefore described.

For convenience, in the appended claims, I 75

have referred to the clamping blocks 16 as "primary" clamping blocks, and the blocks 17 as "secondary" clamping blocks.

Having thus described my invention, what I

5 claim is:

1. An apparatus for bonding the ends of wire ropes, comprising a clamping vise having jaws, a pair of primary clamping blocks arranged between the jaws of the vise for receiving wire rope 10 as it comes from the supply reel, a pair of secondary clamping blocks also arranged between the vise jaws and in interspaced relation with the primary clamping blocks, each of said primary clamping blocks being provided with a pivot pin, 15 engageable with the coacting jaw of the vise, each of the secondary clamping blocks being pivotally attached to its coacting vise jaw by means of a screw, each secondary block being slidably mounted upon the pivot screw and so arranged 20 as to have a limited axial movement thereon, and each of said blocks being formed in its adjacent face with a groove for the reception of a wire rope.

2. An apparatus for bonding the ends of wire 25 ropes, comprising a clamping vise having jaws, a pair of primary clamping blocks arranged between the jaws of the vise for receiving wire rope as it comes from the supply reel, a pair of secondary clamping blocks also arranged between 30 the vise jaws and in interspaced relation with the primary clamping blocks, each of said primary clamping blocks being provided with a pivot pin, engageable with the coacting jaw of the vise, each of the secondary clamping blocks being pivotally 35 attached to its coacting vise jaw by means of a screw, each secondary block being slidably mounted upon the pivot screw and so arranged as to have a limited axial movement thereon, stops carried by the pairs of blocks for limiting the 40 inward rotation thereof, and each of said blocks being formed in its adjacent face with a groove for the reception of a wire rope.

3. An apparatus for bonding the ends of wire 45 ropes, comprising a clamping vise having jaws, a pair of primary clamping blocks arranged between the jaws of the vise and disposed at one end of such jaws for receiving wire rope as it comes from the supply reel, a pair of secondary clamping blocks also arranged between the vise 50 jaws and disposed at the opposite end of the jaws, said pairs of blocks being interspaced from and independent of each other, a pivot for each of the blocks carried by the vise jaws, stops carried by the pairs of blocks for limiting the inward

rotation thereof, said stops being independent of the pivots of the blocks, and each of said blocks being formed in its adjacent face with a groove for the reception of a wire rope.

4. An apparatus for bonding the ends of wire 5 ropes, comprising a clamping vise having jaws, a pair of primary clamping blocks arranged between the jaws of the vise and disposed at one end of such jaws for receiving wire rope as it comes from the supply reel, a pair of secondary 10 clamping blocks also arranged between the vise jaws and disposed at the opposite end of the jaws, said pairs of blocks being interspaced from and independent of each other, each of said blocks being formed in its adjacent face with a groove 15 for the reception of a wire rope, a pivot for each of the blocks carried by the vise jaws, the axis of each pivot being disposed in a plane at right angles to the axis of the groove of the block, stops carried by the pairs of blocks for limiting 20 the inward rotation thereof, said stops being independent of the pivots of the blocks.

5. An apparatus for bonding the ends of wire 25 rope, comprising two pairs of interspaced clamping blocks for holding the rope at fixed, separated points, the blocks of each pair being each formed in its inner adjacent surface with a clamping groove, a separate pivot for each of the blocks, the axes of the pivots of the blocks of each pair being in alignment with each other and at right 30 angles to the axes of the grooves, and single, common operating means for moving the blocks of each pair toward and away from each other in unison, whereby the blocks of each pair will be mounted in substantial alignment with each 35 other.

6. An apparatus for bonding the ends of wire 40 rope, comprising two pairs of interspaced clamping blocks for holding the rope at fixed, separated points, the blocks of each pair being each formed in its inner adjacent surface with a clamping groove, a separate pivot for each of the blocks, the axes of the pivots of the blocks of each pair being in alignment with each other and at right 45 angles to the axes of the grooves, limiting means for each pair of blocks for limiting the opening of the blocks to an amount less than the diameter of the rope, and single, common operating means for moving the blocks of each pair toward and away from each other in unison, whereby the 50 blocks of each pair will be mounted in substantial alignment with each other.

FRANK E. STAHL.
